UNITED STATES PATENT OFFICE.

ALBERT D. GROVER, OF NEW YORK, N. Y., ASSIGNOR, BY MESNE ASSIGNMENTS, TO AUTOSALES CORPORATION, A CORPORATION OF NEW YORK.

COIN-CONTROLLED VENDING-MACHINE.

1,330,073.

Specification of Letters Patent. Patented Feb. 10, 1920.

Application filed April 8, 1916. Serial No. 89,752.

To all whom it may concern:

Be it known that I, ALBERT D. GROVER, a citizen of the United States, and a resident of New York city, in the county of New York and State of New York, have invented certain new and useful Improvements in Coin-Controlled Vending-Machines, of which the following is a specification.

My invention relates to coin-controlled vending machines and has for its object the provision of a machine of small dimensions and large capacity.

Vending machines which are adapted for use in theaters and other places where but little space is available, must be of small dimensions, particularly as to depth, so as not to constitute an obstruction. At the same time the machine should have a sufficiently large capacity to obviate frequent filling. This is especially desirable in the case of machines installed for operation in moving picture theaters or the so-called continuous vaudeville houses where no opportunity is afforded for replenishing the machines after the beginning of the performance until after the close.

The machine of my invention fulfills the above and other requirements, in that it is of small outside dimensions, has a coin-controlled mechanism which is exceedingly simple in construction and efficient in operation, and is provided with a goods-magazine which occupies almost the full height of the casing and thereby provides the machine with a maximum capacity.

The various objects and advantages of my invention will become apparent from a detailed description of the accompanying drawings which form part of this specification and which show an embodiment of my invention in the form in which it is now best known to me.

In the drawings—

Figure 1 is a front view of a machine embodying my invention, the cover plate for the coin mechanism being omitted and a portion of the front wall of the casing being broken away for the sake of clearness to show certain parts within the casing.

Fig. 2 is a side view of Fig. 1, looking from right to left, a portion of the side wall of the casing being broken away to show the gate which normally closes the delivery opening.

Fig. 3 is a top plan view of Fig. 1.

Fig. 4 is a rear view of the machine with the rear wall of the casing broken away to show the working parts within, the parts being shown in normal position.

Fig. 5 is a vertical cross-section approximately on line 5—5 of Fig. 4, looking in the direction of the arrows.

Fig. 6 is a transverse cross-section approximately on the broken line 6—6 of Fig. 4, looking downwardly.

Fig. 7 is a fragmentary detail view showing how the coin is locked against return movement after being carried into the machine a predetermined amount.

Fig. 8 is a view similar to Fig. 4 with the parts shown in full operated position to eject a piece of goods.

Fig. 9 is a longitudinal section approximately on the broken line 9—9 of Fig. 8, looking in the direction of the arrows.

Fig. 10 is a top plan view approximately on the broken line 10—10 of Fig. 8 looking downwardly.

Fig. 11 is a fragmentary detail view showing the ejector and gate in normal position.

Fig. 12 is a view similar to Fig. 11, showing a piece of goods partly ejected from the magazine with the gate just opened to allow the goods to pass through.

Fig. 13 is a view similar to Figs. 11 and 12, with the piece of goods fully ejected, the ejecting lever having partly returned to normal position.

Fig. 14 is a fragmentary detail view showing how the segment which supports the goods during the ejecting operation is tripped by the bottom piece of goods, as the ejecting operation begins, into a position to slide readily beneath the second piece of goods; and

Fig. 15 shows how the ejecting lever is locked against return movement when the magazine is empty.

The closed outer casing of the machine is preferably made in two separable sections, 100 which for the sake of distinction I will designate as a flat section and a box-like section. The flat or rear section comprises a rear wall 1 having side flanges 2, a top 3 and a bottom flange 4. The front or box-like section comprises a front wall 5 provided with a bottom 6 and sides 7 and 8. The two sections of the casing are formed of suitable metal and when assembled they fit against each other to constitute a closed casing. The 110

sides 7 and 8 of the front or box-like section fit against the side flanges 2 and top 3 of the rear or flat section, and the bottom 6 of the box-like section fits over the lower flange of the flat section. Suitable locking means is provided for holding the sections in locked relation. The construction of the outer casing may, of course, be varied and I mention the foregoing construction merely by way of illustration.

Within the casing is supported an upright goods-magazine designated as a whole by M. This magazine is preferably formed of sheet metal and comprises a main wall 9, side walls 10 and longitudinal flanges 11 which serve to retain the pieces of goods in the magazine. The magazine is rigidly held in place by any suitable means. In the present illustration the magazine is supported by the stud 12 near the bottom and by a pair of studs 13 near the top. The stud 12 also performs another function, as will appear later on.

The bottom of the magazine is formed by a plate member 14 which is secured to the frame of the magazine by means of the upwardly turned rear flange 15 and the side piece 16. The flange 15 is fastened to the side wall 10 of the magazine and the side piece 16 is fastened to one of the flanges 11. The bottom plate 14 of the magazine is provided with a laterally and upwardly extending portion 17 which guides the ejected package from the delivery opening 18 at the bottom of the magazine to the discharge opening 19 formed in the side wall 7 of the casing. It will be observed that the discharge opening 18 of the magazine is below the delivery opening 19. The advantage of this construction will be explained later on.

On the side wall 7 is slidably mounted a gate 20 which is held in place by studs 21 extending from the side wall of the casing. The studs 21 extend through slots 22 in the gate. This pin-and-slot connection also limits the up and down movement of the gate. In its normal position as shown in Figs. 1, 2, 4 and 11, the gate 20 fully covers the delivery opening 19. The position of the gate 20 is directly under the control of the ejecting lever 23 which is pivoted on the stud 24 secured to the front wall 5 of the casing. The lever 23 may be referred to as a two-armed lever, having an upper arm 23^a and a lower arm 23^b, the point of pivot 24 being between the two arms. The lever 23 may be provided with an extension 25 to the outer end of which is secured the lower end of a contractile spring 26, the upper end of which is secured to the pin or stud 27 projecting from the side wall 8 of the casing. The spring 26 holds the ejecting lever 23 normally in the position shown in Fig. 1 and returns it to that position after each operation of the machine. Of course, any suit-

able spring means can be employed to maintain the ejecting mechanism in normal position and automatically restore it to that position after each ejecting operation. It will be observed from Figs. 5 and 9 that the lever 23 is mounted and operates within the shallow space or chamber formed between the magazine and the front wall 5 of the casing. I might here explain that when I refer to the wall or plate 5 of the casing as the front wall or plate, I use the word "front" merely in a relative sense, and I so want the word understood when used in certain of the appended claims. In the broader aspect of my invention, so far as the delivery mechanism is concerned, it is immaterial whether the wall or plate which carries that mechanism constitutes the front or the rear of the casing when secured for operation to a suitable support, such as the back of a theater chair.

At its lower end the lever 23 is provided with a laterally and rearwardly extending pin 28 which projects into the magazine through the rear slot 29 and lateral slot 30 thereof to push the bottom piece of goods through the discharge opening 18 and the delivery opening 19 when the lever 23 is operated. The position of the ejected package is shown at P in Figs. 8 and 13. Broadly speaking, the pin 28 may be referred to as an ejecting device operatively connected with the lever 23.

The lever 23 controls and operates the gate 20 through the arm 31 pivoted at 12 on the front plate 5. The arm 31 is at one end provided with a rearward extension 32 arranged to engage between the spaced lugs 33 of the gate 20. The other end of the arm 31 is formed with an irregularly shaped 105 cam slot consisting of the portions 34, 35 and 36. From the lever 23 extends a pin 37 which engages in the cam slot of the arm 31. During the normal position of the parts, as shown in Figs. 4 and 11, the pin 37 of the lever 23 rests at the extreme outer end of the cam slot—that is to say, in the portion 34. As the slot portion 34 is substantially in an arc struck up from the pivot point 24 of the lever 23, the engagement of the pin 37 in the slot portion 34 positively locks the gate 20 in closing position. During the initial movement of the lever 23 toward the left (as viewed in Figs. 4 and 11), there is no corresponding movement of the gate 20, but as soon as the pin 37 enters the raising slot portion 35, the arm 31 is turned clockwise (as viewed in Figs. 4, 8 and 11), and the gate 20 is raised to fully uncover the delivery opening 19. This open position of the gate, with the corresponding position of the pin 37 in the cam slot, is shown in Fig. 12. The operation of the gate 20 is so timed with respect to the movement of the ejecting lever 23, that the gate is fully opened just 130

as the bottom piece of goods is about to be projected through the delivery opening 19, as Fig. 12 clearly shows. Continued operation of the ejecting lever 23 from the position shown in Fig. 12, will push the bottom package P through the delivery opening 19 until it reaches the position shown in Figs. 8 and 13. The position of the lever 23 at the end of its ejecting movement is shown in Fig. 8. During the time that the pin 37 passes through the slot portion 36 there is no movement of the arm 31, because the slot portion 36, when the arm 31 is in the position shown in Fig. 12, forms approximately an arc struck up from the pivot point 24 of the lever 23 as a center. The slot portion 36 is, therefore, a rest or dwell portion and serves to hold the gate 20 in open position during the final forward movement of the ejecting lever as well as during the initial return movement thereof. Fig. 13 shows the lever 23 partially returned to normal position and about to close the gate 20. The gate will, of course, not close until the ejected piece of goods P has been withdrawn from the machine. As soon as the gate 20 is thus released, the spring 26 draws the lever 23 and the connected parts back to normal position.

One of the important features of my invention is the means which I have provided for holding the second piece of goods (and, of course, the rest of the stack or column) above the discharge opening 18 of the magazine during the time that the gate 20 is open. In this way it is impossible to obtain two pieces of goods from one operation of the machine. In the preferred form of my invention, this supporting means is in the form of a segment 38 mounted on the ejecting pin 28. The normal position of the segment 38 is that shown in Fig. 11. When the ejecting operation begins, the rear edge of the bottom piece of goods strips the segment into the position shown in Fig. 14. A further movement of the lever 23 causes the forward edge 39 of the segment to enter the slot 40 formed in the bottom plate 14 and engage the downwardly bent tongue 41 over which the segment 38 rides and is gradually and easily lifted into engagement with the second piece of goods P², as best shown in Fig. 12. In this way, the second piece of goods, and all those above it, are supported out of alignment with the discharge opening of the magazine during the ejecting operation of the lever 23. It is, therefore, absolutely impossible to withdraw the second piece of goods, even should the gate 20 be held open by some instrument after the previously ejected piece had been withdrawn. If we imagined the ejected piece P withdrawn, as shown in Fig. 13, and the gate 20 held open by a knife blade or other instrument, the second piece P² would drop

into the dotted-line position P', indicated in Fig. 12. It will be clear from that figure that the package P' is firmly wedged or locked against withdrawal by the extension 17 of the bottom plate 14, the supporting segment 38 and the upper edge of the discharge opening 18 of the magazine. It will thus be seen that the supporting segment 38 positively prevents the withdrawal of more than one piece of goods at each operation of the machine. When the lever 23 begins its return movement, as indicated by the arrow a in Fig. 13, the segment 38 rolls under the goods in the direction indicated by the arrow b in Fig. 13. In thus rolling the segment 38 causes no frictional retarding of the lever 23 and adds to the smooth and easy operation of the parts. When the lever 23 reaches the end of its return movement, the segment 38 falls back into its normal position, as shown in Figs. 4 and 11, ready to repeat the movements above described at the next operation of the machine.

The movements of the supporting segment 38 and gate 20 are so timed relatively to each other that the segment is in supporting position as long as the gate is open. In other words, the goods are always elevated against attempted withdrawal while the delivery opening 19 is left open by the gate. It will be seen from Fig. 13 that after the ejected package P has been withdrawn and the lever 23 allowed to return, as soon as the pin 37 enters the inclined slot portion 35 of the arm 31, the gate 20 begins to descend. The segment 38 remains in supporting position until the pin 37 leaves the slot portion 35 and enters the slot portion 34, but by that time the opening 19 has been closed by the gate 20.

I have provided means to lock the ejecting lever 23 against full return movement when the supply of goods in the magazine is exhausted. On top of the stack of goods rests a weight or follower W which has a recess 42 on its underside. After the last package has been ejected and the parts return to normal position, the segment 38 engages in the slot 42 of the weight W and thereby locks the lever 23 with its connected parts against further movement. This locked position of the parts is shown in Fig. 15.

If desired, a spring gate 43 may be pivoted at the bottom of the magazine to close the discharge opening 18, as an additional safeguard for the goods. While the goods cannot be removed from the machine except by operation of the ejecting mechanism, quite irrespective of the gate 43, the use of this additional gate prevents the insertion of a sharp-pointed instrument to mutilate the goods. However, the use of the gate 43 is by no means necessary, and I mention it merely as a matter of preference.

I will now describe the coin mechanism by means of which the ejecting lever 23 is actuated into ejecting position upon the deposit of a proper coin. To the front plate 5 of the casing is secured a casting or frame-piece designated as a whole by F. This frame-piece is held in place by suitable fastening devices such as screws or bolts 44 which enter the frame-piece from the inside of the casing, so as to prevent possible removal from the outside. The fastening members 44 enter the openings 44' of the frame-piece F, as shown in Fig. 1. The supporting frame-piece F is shallow and so does not project much beyond the front plate 5 of the casing, as clearly shown in the drawings. On its inner side the frame-piece F is formed with a recess or chamber which forms the coin-passage 45 and in which the rotatable coin-carrier 46 is operatively mounted. This coin-carrier comprises a disk having opposite notches 47 which receive the deposited coin and carry it through the coin-passage into engagement with the pin 48 projecting forwardly from the upper end of the lever 23. The front plate or wall 5 of the casing is provided with an arcuate slot 49 through which the pin 48 projects, as best shown in Fig. 5. The coin-carrier 46 is secured to the inner end of the stud 50 which projects through the frame-piece F and carries at its outer end a suitable form of finger piece 51.

In a recessed portion 52 formed in the inner wall of the frame-piece F is movably mounted a latch member 53 provided with a lateral portion 54 which extends into the coin-chute 45 and is, therefore, in the path of the moving coin. The extension 54 has a beveled edge 55 which the descending coin engages to move the latch member 53 out of obstructing position. After the coin has been carried downwardly in the coin-carrier past the beveled edge 55 of the latch member 53, the coin becomes locked against return movement by the straight edge 56 of the extension 54 engaging the edge of the coin. Fig. 7 shows the coin in a position in which it has just been locked against return movement by the member 53. In other words, after the coin has been carried into the machine a predetermined distance, the coin-carrier cannot be rotated reversely, but the forward movement must be completed. The latch member 53 is returned to normal position by a spring 57 mounted in the slot or recess 58 of the latch member. The lower end of this spring bears against a fixed lug 59 projecting rearwardly from the front wall 5 of the casing, while the upper end bears against the top of the slot or recess 58.

The operation of the coin-mechanism as so far described will now be clearly understood and may be briefly summarized as follows: When a coin is inserted into the coin-

entrance slot 60, it falls on to the edge of the coin-carrier 46. If neither of the coin-receiving notches 47 happen to be in proper position, the coin will rest on the peripheral edge of the coin-disk 46. When the finger piece 51 is then rotated clockwise (as viewed in Fig. 1—or counter-clockwise, as viewed from the rear of the machine, as shown in Figs. 4 and 8), the coin will drop into one of the notches 47 and will be carried by the disk 46 through the coin-passage 45. The upper wall 61 of the coin-passage is so curved as to retain the deposited coin C in the carrier. As the coin descends it rides over the inclined edge 55 of latch member 53 and thereby pushes the latter out of the way. As rotation of the coin-carrier continues, the coin is brought against the pin 48 of the ejecting lever 23, whereupon the latter is rocked to eject the bottom piece of goods, as previously described in detail. The position of the coin when the lever has been moved into full operative position is indicated at C in Fig. 8. Continued rotation of the coin-carrier raises the coin over the pin 48 and allows it to drop into the passage way 62 whence it slides over the inclined portion 63 of the frame-piece F into the shallow chamber between the front wall of the casing and the magazine M. A suitable coin-box 64 may be placed at the bottom of the casing to receive the discharged coins.

On the stud 65 projecting from the front plate 5 of the casing is pivoted the gravity latch 66 which carries at its upper end a pin 67 projecting forwardly through the slot 68 in the plate 5 into the path of movement of the extension 54 of the latch slide 53. The latch 66 has a weighted portion 69 which normally holds the pin 67 in position to engage the lower edge 70 of the extension 54 of the slide 53, as shown in Fig. 8. The gravity latch 66 is provided with an arm 71 which is engaged by the ejecting lever 23, when the latter is in normal position as shown in Fig. 4. When the gravity latch 66 is so held by the lever 23, the pin 67 is out of alignment with the latch slide 53, as shown in Fig. 4. However, as soon as the lever 23 moves out of normal position, the gravity latch 66 swings into its normal or locking position to prevent complete downward movement of the latch slide or member 53. Therefore, should a coin be deposited when the supply of goods is exhausted, the coin-carrier will be stopped against rotation as soon as the coin has pressed the latch member 53 downwardly into engagement with the pin 67 of the gravity latch 66. This occurs before the coin has reached the locking position shown in Fig. 7, so that reverse rotation of the coin-carrier is permitted to carry the coin back through the coin-entrance slot 60 for 130

removal by the intending purchaser. In this way the loss of the deposited coin is prevented when there are no goods in the machine.

5 The lever 23 is at its upper end provided with a curved extension 72 which has teeth 73 adapted to receive the double-acting pawl 74 pivoted on the stud 75 projecting rearwardly from the front plate 5. The pawl 74 is held in normal position by a suitable spring 76 supported from the pin or stud 77 carried by the front plate 5. The two-way pawl 74 by engaging the teeth 73 prevents the return of the lever 23 until the 10 package of goods has been fully ejected.

I have also shown coin-testing mechanism associated with the coin-carrier to prevent operation of the lever 23 with magnetic disks and washers. This coin-testing mechanism 15 is mounted in the recess or chamber 78 formed in the front wall of the supporting frame-piece F. A plate f covers the recess chamber 78. The magnetic coin tester comprises a permanent magnet 79 mounted to swing on the pin or stud 80 carried by the frame-piece F. The poles 81 of the magnet are bent to extend through an opening 82 in the frame-piece F approximately flush with the front wall of the coin-passage 45, as 20 best shown in Fig. 6. At its lower end the magnet, or the frame on which it is mounted, carries a stop 83 which is normally out of alignment with the slot or recess 84 in the latch member 53, as shown in Figs. 4 and 30 8. When a magnetic disk is deposited and carried past the poles of the magnet, the magnetic attraction will swing the magnet toward the left (as viewed in Figs. 4 and 8), and thereby bring the stop 83 into alignment with the slot 84 of the latch member 35 53. Continued movement of the magnetic disk in the coin-carrier will deflect the latch member 53 downwardly until arrested by the stop 83 engaging in the slot 84. This 40 positively locks the magnetic disk and coin-carrier against further movement. However, the coin-carrier may be rotated in the reverse direction to carry the magnetic disk back through the coin-entrance slot whence 45 it may be removed.

To prevent the operation of the machine when a non-magnetic washer is deposited, I provide a pawl 85 pivotally mounted at its lower end in the lug 86 which is arranged in 50 the chamber 78 of the frame-piece F, as best shown in Fig. 1. At its outer end the pawl 85 extends through an opening in the frame-piece into the coin-passage 45 so as to be in the path of the moving coin. A suitable 55 spring 87 mounted on the stud 88 of the frame-piece F presses the pawl 85 and yieldingly holds it in the path of the coin. When a good coin is in the coin-carrier the pawl 85 is repressed and allows the coin to pass. 60 However, when a ring or washer is in the

coin-carrier, the upper end of the pawl 85 snaps into the opening of the ring or washer and thereby locks the same against further entrance into the machine. The head of the pawl is beveled on the underside so that the 70 locked ring or washer may be withdrawn by rotating the carrier in the reverse direction.

The above described magnetic coin-tester and washer-catcher form no part of my present invention, but are the joint invention 75 of Earl E. Barber and myself, and form the subject-matter of the co-pending Grover and Barber application, Serial No. 762,810, filed April 22, 1913, and the divisional application, Serial No. 58,544, filed October 29, 80 1915.

Although I have herein described and shown a machine of specific construction, I would have it distinctly understood that I do not intend to be limited to the details of 85 construction herein set forth, as it is obvious that the various features of novelty which characterize my invention may be mechanically carried out in other ways than that set forth by way of illustration.

Having thus described my invention what I claim as new and desire to secure by Letters Patent of the United States, is:

1. In a vending machine, a shallow and substantially rectangular outer casing provided with a delivery opening in its lower portion, an upright magazine supported within said casing and having a discharge opening at its lower end, there being a shallow space or chamber between said magazine and the front wall of said casing, a lever comprising an upper arm and a lower arm and pivoted at a point between its arms to operate in said shallow chamber, an ejecting device connected with the lower arm of 95 said lever to eject the goods from the lower end of said magazine into said delivery opening for removal, a rotatable member mounted on the front wall of said casing on the outside thereof, and a second rotatable member mounted within the casing and operatively connected with said first rotatable member, said second rotatable member being adapted to become operatively connected with the upper arm of said lever, said rotatable members and said lever being mounted to operate in planes substantially parallel with the plane of the casing.

2. In a vending machine, a shallow and substantially rectangular outer casing provided with a delivery opening in its lower portion, an upright magazine supported within said casing and having a discharge opening at its lower end, there being a shallow space or chamber between said magazine and the front wall of the said casing, a lever pivoted on the front wall or plate of said casing to operate in said shallow chamber in a plane parallel with the plane of the casing, said lever comprising an upper arm 120

- and a lower arm between which the lever is pivoted, an ejecting device connected with the lower arm of said lever to eject the goods from the lower end of said magazine into 5 said delivery opening for removal, and hand-operable rotary mechanism mounted on the front plate of said casing for engaging the upper arm of said lever and thereby actuating the same into ejecting position, 10 said mechanism being rotatable in a plane or planes parallel with the plane of the casing.
3. In a vending machine, an upright magazine for the vendible goods, said magazine having a discharge opening at its lower end, 15 a movable member having means for pushing the bottom package through said discharge opening, a segment swingingly mounted on said member for supporting the stack of goods above said discharge opening 20 during the ejecting operation of said member, and means engaging said segment for automatically swinging it into supporting position during the ejecting operation of said member.
- 25 4. In a vending machine, an upright magazine for the vendible goods, said magazine having a discharge opening at its lower end, a pivoted lever having a lateral pin or extension for engaging the bottom package 30 and pushing the same through said discharge opening, a device movably mounted on said lever and carried thereby over the bottom of said magazine underneath the stack of goods to support the same above 35 said discharge opening during the ejecting operation of said lever, and means for automatically moving said device into supporting position during the ejecting operation of said lever.
- 40 5. In a vending machine, an upright magazine for the vendible goods, said magazine having a discharge opening at its lower end, a pivoted lever having a lateral pin or extension for engaging the bottom package 45 and pushing the same through said discharge opening, a segment swingingly mounted on said pin or extension for supporting the stack of goods above said discharge opening during the ejecting operation of said lever, and means for automatically swinging said segment into supporting position during the ejecting operation of said lever.
- 55 6. In a vending machine, a casing having an upright goods-magazine slightly spaced from the front wall thereof, said magazine having a lateral discharge opening at its lower end and a slot across the lower end of its front wall, a lever pivotally mounted 60 in the shallow space between the front wall of the casing and the front wall of said magazine, and a transverse extension at the lower end of said lever and adapted to sweep across the bottom of said magazine to push
- the lowermost package out of said lateral discharge opening, said extension projecting into the magazine through said slot.
7. In a vending machine, a casing having an upright goods-magazine slightly spaced from the front wall thereof, said magazine 70 having a lateral discharge opening at its lower end and a slot across the lower end of its front wall, a lever pivotally mounted in the shallow space between the front wall of the casing and the front wall of said magazine, a transverse extension at the lower end of said lever and adapted to sweep across the bottom of said magazine to push the lowermost package out of said lateral discharge opening, said extension projecting 75 into the magazine through said slot, and means movably mounted on said extension for supporting the stack of goods above said discharge opening during the ejecting operation of said lever.
8. In a vending machine, a casing having an upright goods-magazine slightly spaced from the front wall thereof, said magazine having a lateral discharge opening at its lower end and a slot across the lower end of its front wall, a lever pivotally mounted in the shallow space between the front wall of the casing and the front wall of said magazine, a transverse extension at the lower end of said lever and adapted to sweep 80 across the bottom of said magazine to push the lowermost package out of said lateral discharge opening, said extension projecting into the magazine through said slot, and a segment pivoted on said extension for supporting the stack of goods above said discharge opening during the ejecting operation of said lever.
9. In a vending machine, a closed outer casing having a delivery opening in one of its side walls, an upright goods-magazine having a lateral discharge opening below said delivery opening, means for ejecting the bottom package from said magazine, means for guiding the ejected package upwardly from said discharge opening through said delivery opening, and means for supporting the goods in the magazine above said discharge opening during the ejecting operation, whereby a second piece of goods 90 partly withdrawn before the ejecting means returns to normal position becomes wedged against complete removal between said guiding and said supporting means.
10. In a vending machine, a closed outer casing having a delivery opening in one of its side walls, an upright goods-magazine having a lateral discharge opening below said delivery opening, means for ejecting the bottom package from said magazine, and means whereby a second piece of goods removed from its normal position in the magazine before said ejecting means returns to 95

normal position is locked against complete removal.

11. In a vending machine, an upright magazine for the vendible goods, said magazine having a discharge opening at its lower end, a movable member having means for pushing the bottom package through said discharge opening, a segment pivotally mounted on said member for supporting the stack of goods above said discharge opening during the ejecting operation of said member, and a weight or follower in said magazine adapted to engage said supporting means and thereby lock said member against full return movement when the magazine is empty.

12. In a vending machine, an outer casing provided with a delivery opening, an upright magazine for containing the vendible goods and having a discharge opening at its lower end, a hand-operable device having means for engaging the bottom package and pushing it part way through said discharge and delivery openings, so that the ejected package remains supported in the delivery opening of the casing until removed, means connected with said device and independent of said ejecting means for supporting the stack of goods above said discharge opening during the ejecting operation, a movable gate for normally closing said delivery opening, and operative connections between said device and said gate for automatically moving said gate into open position during the ejecting movement of said device, said connections being such that said device is held locked in actuated position until the gate is released by the removal of the ejected article.

13. In a vending machine, an outer casing provided with a delivery opening, a movable gate for normally closing said opening, an upright magazine for containing the vendible goods and having a discharge opening at its lower end, a hand-operable device having means for engaging the bottom package and pushing it part way through said discharge and delivery openings, means mounted on said device and independent of said ejecting means for supporting the stack of goods above said discharge opening during the ejecting operation, and operative connections between said device and said gate for automatically moving said gate to open position during the ejecting movement of said device, said connections automatically locking said device against return movement while said gate is in open position.

14. In a vending machine, a shallow and substantially rectangular casing consisting of a flat section and a box-like section separably held together, a magazine supported within said casing for containing a stack of vendible goods, there being a shallow space or chamber between said magazine and the front wall or plate of said box-like section,

a lever pivoted intermediate its ends on said front plate to operate in said shallow chamber in a plane parallel with the plane of the casing, an ejecting device connected with one end of said lever for discharging the goods from the lower end of said magazine, and hand-operable rotary mechanism mounted on the front of said box-like section and adapted to be connected with the other end of said lever, said mechanism being operable in a plane or planes parallel with the plane of the casing.

15. In a vending machine, a shallow and substantially rectangular casing, a magazine supported within said casing for containing a stack of vendible goods, there being a shallow space or chamber between said magazine and the front wall or plate of said casing, a lever pivoted intermediate its ends to operate in said shallow chamber in a plane parallel with the plane of the casing, an ejecting device connected with one end of said lever for discharging the goods from the lower end of said magazine, a supplemental casing secured to the front wall of said main casing, said supplemental casing being provided with a shallow recess, a member operable in said recess and adapted to be connected with the other end of said lever to operate the same, and hand-operable means carried by said supplemental casing for operating said member.

16. In a vending machine, a casing having a delivery opening, a movable gate for normally closing said opening, a magazine for the vendible goods, a pivoted lever for ejecting the goods from said magazine, a pivoted arm connected at one end with said gate and having a cam slot at its other end, and a pin projecting from said lever into said cam slot to operate said arm and gate during the movement of said lever, said cam slot being so constructed and arranged that in the normal position of the lever said gate is locked in closed position.

17. In a vending machine, a casing provided with a delivery opening, a movable gate for normally closing said delivery opening, a magazine for the vendible goods having a discharge opening, hand-operable mechanism having a member for engaging the goods and ejecting them through said discharge and delivery openings, connections between said mechanism and said gate for moving said gate into open position during the ejecting movement of said mechanism, and means carried by said mechanism and independent of said member for preventing the withdrawal of a second piece of goods while said gate is open.

18. In a vending machine, an upright magazine for containing the vendible goods, means for ejecting the bottom piece of goods from said magazine, a swinging antifriction device movable beneath the goods to

support them during the ejecting operation, and means for automatically raising said device into supporting position during the ejecting operation.

5 19. In a vending machine, an upright magazine for containing the vendible goods, means for ejecting the bottom piece of goods from said magazine, a swinging antifriction device carried by said means and movable

beneath the stack of goods to support them 10 during the ejecting operation, and means for automatically raising said device into supporting position during the ejecting operation.

In witness whereof, I hereunto subscribe 15 my name this 3 day of April, 1916.

ALBERT D. GROVER.
